UNITED STATES PATENT OFFICE.

WILLIAM B. SHATTUC, OF CINCINNATI, OHIO.

RAILROAD-TICKET.

SPECIFICATION forming part of Letters Patent No. 239,859, dated April 5, 1881.

Application filed May 12, 1880. (Model.)

To all whom it may concern:

Be it known that I, WILLIAM B. SHATTUC, of Cincinnati, in the county of Hamilton and State of Ohio, have invented a new and useful Improvement in Railroad-Ticket Books, of which the following is a specification.

My invention, while applicable to various forms of commutation passage-tickets, is more especially designed for what are known as 10 "thousand-mile tickets." The ordinary form of such a ticket is a book containing one thousand separable coupons, consecutively numbered, each good for one mile of travel.

The form of thousand-mile ticket customarily employed is found to be imperfect and unsatisfactory to the railroad-managers, because an inadequate check on holders who have abused the special privilege, and it is unsatisfactory to the general traveler who finds such 15 mutants enjoying advantages not possessed by him. A railway passage-ticket, whether single or multiple, always, as is well known, implies the right to conveyance of accompanying baggage not in excess of a prescribed 20 weight, say one hundred and fifty pounds. The passenger who desires to carry baggage presents his ticket to the baggage-master, who punches it with the letter "B." Even should the passenger not accompany his baggage, the 25 punch aforesaid is an absolute check on any attempt of a double use of the ticket for baggage privileges. In practice passengers seldom desire or avail themselves of their full 30 privileges in this respect, so that the average 35 baggage-weight per traveler is only a small fraction of the permitted maximum, and a passenger who fails to avail himself of his full baggage privileges on one trip cannot recoup on the next; but in the case of a commutation- 40 ticket composed of a multitude of such mile coupons the above-mentioned precautions are impracticable, because in the hurry of departing trains the punching of each individual coupon would consume very much more time than 45 the baggage-master has at his disposal, and hence he is obliged to depend wholly on the good faith of the ticket-holder. With the majority of holders he would, of course, be perfectly safe in so doing; but experience has 50 proven that a numerous minority of holders have abused the trust by using it for the gra-

tuitous shipment of merchandise many times in excess of their contract.

To make impossible such clandestine use of commutation privileges is the object of my invention. 55

My improvement consists in a coupon-book in which is provided with each mile-passage coupon, or with each group of two or more such coupons, a baggage coupon or tag corresponding to the same number of miles, and so connected with its passage-coupon as to bring the passage-coupon between the baggage-tag and the stub, so that its detachment will be quickly noticed, the baggage privilege extending only 60 to the remaining passage-coupons having such baggage-coupons in line therewith, the baggage-coupons not being recognized, or of no value, unless accompanied by the associate 65 passage-coupon, which cannot be removed from 70 its associate baggage-coupon without forfeiting its baggage privilege. On the presentation of such a ticket for the purpose of securing free transportation of baggage, the baggage-master will simply separate baggage-coupons 75 corresponding to the distance to which the baggage is to be taken, thus divesting so many of the passage-coupons of their baggage privileges. This is the work of a moment, and, while imposing no inconvenience on respectable 80 commuters, will restrict the holder of such a ticket to the precise privileges as to baggage enjoyed by ordinary passengers, and will put a stop to an abuse of the privilege so injurious and demoralizing as to have caused the entire 85 abolition of such favors to have been seriously debated.

In order that the invention may be fully understood, I will proceed to describe it with reference to the accompanying drawings, in 90 which—

Figure 1 represents one of my improved ticket-books open at the title-page and first page of coupons. Fig. 2 shows the same book opened at the last page of coupons. Fig. 3 95 shows the same opened at the contract-page.

The title and contract pages are preferably pasted on the inside faces of the front and back covers respectively, in the manner illustrated in Figs. 1 and 3. Each book may, of course, 100 contain any number of pages and each page consist of any convenient number of coupons.

My practice is to include on each leaf twenty passenger one-mile coupons in two parallel columns, as represented at A A, and ten corresponding baggage two-mile coupons in another parallel column, B, as in the accompanying drawings. The column B is printed with the sentence "Baggage 2 miles."

In my preferred arrangement, here selected for illustration, the mile-passage coupons are disposed in consecutive pairs between one baggage-coupon and the stub C; but, if preferred, the passage-coupons may be arranged in single column between the stub C and baggage-tags B, and each individual mile-passage coupon be furnished with its attached baggage-coupon, in which case the inscription on the latter would of course be "Baggage 1 mile."

Instead of twenty miles, each page may contain a less number of mile-passage coupons—such, for example, as ten, or four, or even two.

In the act of printing the leaves of my book lines of punctures b are provided between the baggage and passage coupons, and between the consecutive baggage-coupons, similar to those which in my ticket and those heretofore employed partially separate the passenger-coupons, the object of such punctures, of course, being to enable easy separation by hand of any desired number of consecutive tickets.

I am aware that baggage-checks and receipts for stamping have been attached to tickets, and both have had numbers corresponding to the number of the ticket; such a ticket, therefore, I do not claim as my invention, as such tickets are not available for the purpose of preventing fraud as practiced in the use of ordinary coupon-books.

Having thus described my invention, the following is what I claim as new therein and desire to secure by Letters Patent:

As a new article of manufacture, a railroad-ticket book having leaves on which are printed columns of passage-coupons A and baggage-tags B, associated with the said passage-coupons and indicating the extent of baggage privilege, the said passage-coupons being located between the baggage-tags and stub C, and said baggage-tags being adapted to be separated from or with their respective associated passage-coupons, as set forth.

In testimony of which invention I hereunto set my hand.

WILLIAM B. SHATTUC.
